ELECTRIC SWITCH

Clarence W. Kuhn, Milwaukee, Wis., assignor to
Cutler-Hammer, Inc., Milwaukee, Wis., a corporation of Delaware

Application July 3, 1933, Serial No. 678,750

10 Claims. (Cl. 200—124)

This invention relates to electric switches, and more particularly to manually operated switches having automatic means associated therewith for releasing and throwing the switch to off position under overload conditions.

An object of the invention is to provide an improved manually operated switch having a trip free overload mechanism associated therewith, or in other words, a switch which is tripped to open position in response to predetermined current conditions even though the manual operating means is deliberately held in on position.

Another object is to provide an improved switch of the aforesaid character which operates with a snap action when actuated either manually or automatically and which is reset by return of the manual operating means to off position.

Another object is to provide a switch of the aforesaid character having improved overload tripping means associated therewith including overload responsive elements of the self-soldering type.

Another object is to provide a switch of the aforesaid character having improved no voltage protective means associated therewith.

Another object is to provide an improved enclosing casing for switches of the aforesaid character having means associated therewith for indicating tripping of the switch under overload conditions.

Another object is to simplify and generally improve the construction of switches of the above mentioned type and to provide a construction in which practically all of the parts may be cheaply made of molded material and sheet metal stampings.

Various other objects and advantages of the invention will hereinafter appear.

The accompanying drawings illustrate an embodiment of the invention which will now be described, it being understood that the embodiment illustrated is susceptible of modification without departing from the spirit and scope of the appended claims.

In the drawings,

Figure 1 is a front elevational view of a switch embodying the invention;

Fig. 2 is a vertical sectional view taken substantially on line 2—2 of Fig. 1 and illustrating the switch in open position;

Fig. 3 is a sectional view similar to that shown in Fig. 2, illustrating the switch in closed position;

Fig. 4 is a fragmentary vertical sectional view illustrating the operating mechanism in a position for effecting resetting of the overload responsive mechanism;

Fig. 5 is a perspective view of the movable contact element of the switch;

Fig. 6 is a front elevational view of the switch with the movable contact element removed;

Fig. 7 is a perspective view of the snap operating mechanism of the switch;

Fig. 8 is a rear elevational view of the switch with portions broken away and shown in section;

Fig. 9 is a front elevational view of an enclosing casing for the switch;

Figs. 10 and 11 are sectional views on lines 10—10 and 11—11, respectively, of Figs. 9;

Fig. 12 is a fragmentary bottom view of the enclosing casing;

Fig. 13 is a front elevational view of a no voltage release mechanism for the switch shown in Fig. 1, and

Fig. 14 is a side elevational view of the no voltage release mechanism shown in Fig. 13 with portions of the switch shown in section.

Referring to the drawings, the same illustrate a starter for multi-phase alternating current motors including an insulating base 1 having a snap switch mechanism 2 mounted thereon which is provided with contacts for connecting line terminal devices L¹, L², L³ mounted upon the upper end of said base to load terminal devices T¹, T², T³, respectively, mounted upon the lower end of said base. As hereinafter set forth, switch mechanism 2 is of the free tripping type, and base 1 carries a pair of electro-thermal overload devices 3 and 4, each of which is responsive upon predetermined overload conditions in one of the load circuits to effect tripping of said switch mechanism.

The switch mechanism 2 includes a movable contact carrier 5 formed of insulating material and having openings adjacent opposite ends thereof for receiving a pair of guide pins 6—6 mounted upon the front face of insulating base 1 and projecting forwardly therefrom. Said contact carrier is biased outwardly by coil springs 7—7 which surround the guide pins 6—6 and said guide pins are provided with heads on the outer ends thereof which act as stops to limit outward movement of said carrier when the same is moved into the open position shown in Fig. 2. Contact carrier 5 is movable between the open position shown in Fig. 2 and a closed position shown in Fig. 3 by a snap operating mecha-

nism 8 including an actuating lever 10 and a cooperating spring pressed actuated member 11.

Actuating member 10 comprises a sheet metal stamping which is rotatably mounted upon a pin 12 carried by a bracket 13 fixed to the rear face of base 1. As shown in Fig. 7, said actuating member is formed to provide spaced parallel side arms each having a leg 15 projecting downwardly from pivot pin 12, and a leg 16 projecting forwardly from said pin. As shown in Figs. 2 and 3, the legs 16 extend through an opening 17 in base 1 and are connected at their outer ends by a portion 18 to which an operating handle 19 is secured by a screw 20. The legs 15 are located within a recess 21 in the rear face of base 1, and each of said legs has its lower end shaped to provide a cam surface having a crest 22 and inclined faces 23 and 24 on opposite sides thereof.

The actuated member 11 is arranged within an opening 25 in base 1 (Figs. 2 and 3) and has a pin 28 fixed thereto adjacent the inner end thereof which carries a pair of rollers 29—29 arranged to ride upon the cam surfaces on the lower ends of the legs 15. A spring 31 having one end connected to actuated member 11 and its opposite end connected to pin 12 serves to yieldingly hold the rollers 29—29 in engagement with said cam surfaces, and as shown in Figs. 2 and 3 said spring is connected to said actuated member 11 at a point to the left of said rollers to thereby bias the outer end of said actuated member upwardly. The outer end of actuated member 11 is located within a centrally arranged opening in contact carrier 5 and the upper edge thereof is provided with a slot 32 for receiving a latch plate 33 secured to the rear face of contact carrier 5 by rivets 34.

The bracket 13 is provided with a vertically arranged body portion 35 having its upper end secured to base 1 by a screw 36 and having its lower end provided with an offset portion 37 which is secured to said base by a pair of screws 38. The side arms of actuating member 10 are provided with stop projections 40 adjacent the lower ends of legs 15 and with stop projections 41 extending upwardly from pivot pin 12, and as is apparent from Figs. 2 and 3 said stop projections cooperate with the body portion 35 of bracket 13 to limit movement of said actuating member in opposite directions. The securing screws 38 associated with bracket 13 also serve to secure an angle plate 43 to a forwardly extending projection 44 on the front face of insulating base 1, said plate being also secured to said base by a screw 45. As is apparent from Fig. 3, plate 43 cooperates with plate 33 on contact carrier 5 to limit inward movement of said contact carrier and as shown in Figs. 4 and 6 said plate is provided with an inwardly extending portion 46 having a slot 47 therein for receiving the actuated member 11 to guide the latter.

The operation of the aforescribed operating mechanism will now be described. Assuming that the aforescribed parts are in the position shown in Fig. 2, upward movement of the operating handle 19 causes the cam surfaces on the lower ends of legs 15 of actuating member 10 to move outwardly with respect to the rollers 29. During final upward movement of the operating handle 19 into the position shown in Fig. 3 the crests 22 of the cam surfaces assume a position to the left of the axes of rollers 29, whereupon the spring 31 causes said rollers to move inwardly over the cam surfaces 24 to effect snap movement of actuated member 11 and contact

carrier 5 from the open position shown in Fig. 2 into the closed position shown in Fig. 3. It will be noted that when the operating handle 19 is in the position shown in Fig. 3 the rollers 29 engage surfaces 24^a of increased angularity upon the inner ends of cam surfaces 24 to thereby increase the holding force on contact carrier 5 when the same is moved into closed position. Upon return movement of the operating handle 19 from the position shown in Fig. 3 into the position shown in Fig. 2 the cam surfaces on the lower ends of legs 15 of actuating member 10 move inwardly with respect to the rollers 29. During final movement of operating handle 19 into the position shown in Fig. 2 the crests 22 of the cam surfaces assume a position to the right of the axes of rollers 29 and spring 31 then causes said rollers to move outwardly over the cam surfaces 23 to effect snap movement of actuated member 11 and contact carrier 5 from the closed position shown in Fig. 3 into the open position shown in Fig. 2.

As will now be set forth, when contact carrier 5 is moved into the closed position shown in Fig. 3 the aforementioned overload devices 3 and 4 are responsive upon given overload conditions in the circuits connected to terminal devices T¹ and T² to move actuated member 11 out of engagement with plate 33 and thereby permit said contact carrier to move to open position. Also as will now be set forth, the operating handle 19 is returnable from the position shown in Fig. 3 into the position shown in Fig. 2 to effect resetting of either or both of the overload responsive devices 3 and 4 and to also relatch actuated member 11 with plate 33 on contact carrier 5.

Each of the overload devices 3 and 4 includes a vertically arranged tripping member 50 slidably mounted upon the rear face of base 1 and having an overload responsive element 51 of the self-soldering type associated therewith for normally holding the same in a retracted position shown in Fig. 8 against the action of a spring 52. The self-soldering elements 51 are arranged in spaced relation adjacent the lower end of base 1 and their associated tripping members 50 are arranged in opposed relation therebetween. Each of the self-soldering elements 51 includes a heater 53 of helical form, arranged within a recess 54 in the front face of base 1, a tubular member 55 surrounded by said heater and fixed within an opening in said base, and a pin 56 located within said tubular member and normally held against rotation with respect thereto by a solder connection. Each of the pins 56 has an enlarged toothed head 57 on the inner end thereof to be engaged by a spring latch 58 fixed to the lower end of its associated tripping member 50. As shown in Fig. 8 the tripping members 50 are slidably mounted between oppositely disposed L-shaped projections 60—60 on the rear face of base 1 and the same are held in position upon said base by an insulating plate 61 having its lower end secured to said base by a screw 62 and having its upper end supported by the bracket 13. The springs 52 associated with the tripping members 50 are held under compression between projections on the upper ends of said members and the lower legs of projections 60.

The upper ends of the tripping members 50 cooperate with a trigger 64 associated with the actuated member 11. Said trigger is arranged below the actuated member 11 and has a tongue

65 on the inner end thereof to be engaged by either of the tripping members 50 and has its outer end provided with spaced side arms 66—66 which are pivotally mounted upon a pin 5 57 fixed to said actuated member adjacent the slot 32.

As is apparent from the foregoing, the self-soldering overload elements 51 serve to normally hold the tripping members 50 in the positions 10 shown in Fig. 8. However, upon closure of the switch each of the elements 51 is responsive upon given overload conditions to release its associated tripping member 50 and thereby permit upward movement thereof under the action of its 15 associated spring 52. Upon upward movement of either or both of the tripping members 50 the inner end of trigger 64 is moved upwardly and the side arms 66 of said trigger, by engagement with the inwardly extending portion 46 of plate 20 43, effect downward movement of the outer end of actuated member 11. The slot 32 in the actuated member 11 is thus moved out of engagement with latch plate 33 and contact carrier 5 is then moved forwardly into open position with 25 a snap action by its associated springs 7.

It will be noted from Figs. 3 and 7 that the actuated member 11 has an upwardly extending toe projection 68 on the inner end thereof. Upon tripping of the switch the rollers 29 are 30 moved slightly inwardly with respect to the cam surfaces 24^a from the position shown in Fig. 3 under the action of spring 31 and actuated member 11 then assumes a position wherein its toe projection 68 engages a shoulder 69 formed 35 by the offset portion 37 on the lower end of bracket 13. With the actuated member 11 in this position downward movement of the operating handle 19 from the position shown in Fig. 3 causes said actuated member to move downwardly into a position shown in Fig. 4 just prior to movement of said operating handle into the position shown in Fig. 2. As is apparent, during movement of the actuated member 11 into the 40 position shown in Fig. 4 the trigger 64 moves downwardly therewith to return either or both of the tripping members 50 from its tripped position into normal position. Upon return of the handle 19 into the position shown in Fig. 2 the crests 22 of the cam surfaces are moved to 45 the right of the axes of rollers 29 and said rollers then move outwardly over the cam surfaces 23 to effect latching of actuated member 11 with plate 33 on contact carrier 5. In connection with the foregoing it should be noted that during the aforescribed resetting operation the toe projection 68 on actuated member 11 is held 50 in engagement with shoulder 69 on bracket 13 and the outer end of said actuated member is thus biased downwardly into engagement with 55 a surface 70 on plate 33 as shown in Fig. 4. With the actuated member 11 held in this position during resetting operations the tripping members are reset in such positions as to prevent the upper ends thereof from obstructing 60 inward and outward movements of said actuated member and its associated trigger 64 during manual operations of the switch.

As hereinbefore stated the above described switch mechanism is provided with contacts for 65 connecting line terminal devices L¹—L² and L³ mounted upon the upper end of base 1 to load terminal devices T¹—T² and T³, respectively, mounted upon the lower end of said base. As 70 shown in Fig. 5, contact devices 72, 73 and 74 75 are mounted upon the rear face of contact car-

rier 5, the contact devices 72 and 73 being arranged in spaced relation adjacent the upper edge of said carrier, and the contact device 74 being arranged midway between the former contacts and adjacent the lower edge of said carrier. Each of said contact devices includes a U-shaped holder 75 and a U-shaped bridging contact 76 mounted within said holder and movable therein against the action of a spring 77. Each of the contacts 76 is held in assembled 10 relation within its associated holder 75 by inverted end portions 78 on the latter, and as is apparent from Fig. 5 said contacts may be tilted with respect to their associated holders to permit removal thereof. Base 1 is provided with 15 openings for receiving each of the contact devices 72, 73 and 74 and each of said devices cooperates with a pair of spaced stationary contacts mounted within recesses formed in the rear face of said base. 20

As shown in Figs. 6 and 8, the heater 53 of overload device 3 is connected between terminal device T¹ and a binding post 80 and contact device 72 cooperates with a pair of stationary contacts 72^a and 72^b, the former being connected 25 to terminal device L¹, and the latter being connected to binding post 80 by a connection 81. The heater 53 of overload device 4 is connected between terminal device T² and a binding post 82, and contact device 73 cooperates with a pair 30 of stationary contacts 73^a and 73^b, the former being connected to terminal device L² and the latter being connected to binding post 82 by a connection 83. Contact device 74 cooperates with stationary contacts 74^a and 74^b, the former 35 being connected to terminal device L³ by a connection 84 and the latter being connected to terminal device T³ by a connection 85.

As shown in Figs. 9 and 10 the aforescribed switch is provided with a box-shaped enclosing 40 casing 87 provided with a cover 88. Base 1 of the switch is secured to the rear wall of the enclosing casing 87 by securing screws which pass through corner openings in said base and an insulating plate 89 is interposed between said 45 wall and the rear face of said base. The cover 88 is hinged to the upper wall of casing 87, as shown at 90, and the face of said cover is provided with an opening for receiving the operating handle 19 of the switch. A vertically arranged locking bar 91 having an opening therein for receiving the operating handle 19 is mounted upon the rear face of cover 88. Said bar is supported by brackets 92 secured to the rear face of said cover, and the lower wall of 50 casing 87 is provided with an opening 93 for receiving a projecting portion on the lower end of said bar. As shown in Fig. 12, the opening 93 is shaped to provide oppositely disposed inwardly extending locking projections 94—94 for 55 engaging the outer face of locking bar 91 and as shown in Fig. 9 said locking bar is provided with recesses 95—95 on opposite sides thereof for receiving the locking projection 94. When the switch is in closed position, as shown in 60 Fig. 9, the locking projections 94 on casing 87 engage the outer face of locking bar 91 to prevent opening of the cover. However, when the operating handle 19 is moved downwardly into open position the locking bar 91 moves there- 65 with into a position wherein its recesses 95 are aligned with the locking projections 94 and the cover 88 can then be swung outwardly into open position. 70

The cover of the enclosing casing is provided 75

with a mechanism operable by the contact carrier 5 to indicate opening and closure of the switch. A small window 97 is provided in a plate 98 fixed to the front face of cover 88 and through this window a slider 99 bearing legends "on" and "off" is visible. The slider 99 is slidably mounted between plate 98 and locking bar 91 within an opening in cover 88 and is biased upwardly by a spring 100. A button 101 is secured to the inner face of slider 99 and the outer face of contact carrier 5 is provided with a projection having an inclined face 102 for engaging said button. When contact carrier 5 moves into "off" position the face 102 engages the button 101 to move slider 99 downwardly into a position wherein the "off" legend thereon shows within the window 97. Upon movement of contact carrier 5 into on position face 102 moves out of engagement with button 101 and slider 99 is then moved upwardly by its associated spring 100 into a position wherein the "on" legend thereon shows within the window 97.

The enclosing casing 87 and its cover 88 are provided with lock projections 104 and 105, respectively, which are arranged on opposite sides of the locking bar 91. Said locking bar has its lower end provided with a slot 106 and an opening 107 and said lock projections are provided with padlock openings 108 in vertical alignment with slot 106 and padlock openings 109 in vertical alignment with the opening 107. With the switch in on position the lower end of locking bar 91 is located immediately above the openings 109 in the lock projections, and when a padlock is inserted in said openings the switch is locked in on position. Upon opening of the switch the opening 107 in locking bar 91 is aligned with the openings 109 in the lock projections and when the padlock is inserted in said openings the switch is locked in open position. Upon insertion of the padlock in openings 108 cover 88 is locked to the enclosing casing 87 and the locking bar 91 is released to permit closure or opening of the switch.

Referring now to Figs. 13 and 14, the same illustrate a no-voltage release mechanism for the aforescribed switch. The actuating member 10 of the switch is biased towards open position by a spring 111 and is adapted to be held in closed position by a pair of no voltage release magnets 112 and 113 each to be connected in one of the circuits controlled by the switch. Said magnets are mounted upon a plate 114 secured to the rear face of insulating base 1 and the spring 111 is held under compression between a forwardly extending bracket 115 fixed to said plate and a block 116 pivotally mounted upon a pin 117 carried by the forwardly projecting legs 16 of actuating member 10. An operating lever 118 is pivotally secured to the forwardly projecting legs 16 of actuating member 10 by a pin 119 and said operating lever is provided with forwardly projecting arms 120 and upwardly projecting arms 121. An operating handle 122 is secured to the outer ends of arms 120 and the upper ends of arms 121 have an armature member 123 mounted thereon to be attracted by the magnets 112 and 113. The arms 121 also carry a pin 124 having a roller 125 mounted thereon which cooperates with a downwardly extending projection 126 on the front end of bracket 115.

When the operating handle 122 is pressed upwardly from the position shown in Fig. 14, lever

118 is held against clockwise rotation by engagement of roller 125 with the projection 126 on bracket 115. Lever 118 is thus moved upwardly and the actuating member 10 moves therewith to effect closure of the switch. Upon closure of the switch roller 125 moves over the upper end of projection 126, as shown in dotted lines in Fig. 14, and the armature member 123 is then attracted by the electromagnets 112 and 113 to hold the switch in closed position against the action of spring 111. When the operating handle 122 is released spring 111 tends to move the roller 125 outwardly over the upper end of projection 126, but the upper end of said projection is so shaped that a relatively slight holding force on the armature member 123 serves to maintain the switch in closed position against the action of spring 111. Under no voltage conditions the armature member 123 is released and spring 111 then moves the switch to open position. Also by pressing the operating handle 122 downwardly the armature member 123 may be released from the magnets 112 and 113 to effect opening of the switch.

What I claim as new and desire to secure by Letters Patent is:

1. A switch device having a movable contact element biased towards open position, a manual operating member reciprocable to move said contact element between open and closed positions, snap operating mechanism interposed between said operating member and said contact element to move said contact element into and out of open or closed position with a snap action, said mechanism including a latching part adapted to be tripped to disconnect said contact element from said manual operating member, and an overload mechanism responsive to trip said latching part, said latching part and said overload mechanism being resettable by said manual operating member.

2. A switch device having a movable contact element biased towards open position, a manual operating member reciprocable to move said contact element between open and closed positions, snap operating mechanism interposed between said operating member and said contact element to move said contact element with a snap action, said mechanism including a latching part adapted to be tripped to disconnect said contact element from said operating member, and an overload mechanism responsive to trip said latching part, said overload mechanism including a self-soldering overload responsive element, and a spring biased tripping part normally held in a given position by said overload element and movable upon response of said overload element to trip said latching part, said latching part and said tripping part being resettable by said manual operating member.

3. A switch device having a movable contact element biased towards open position, a manual operating member reciprocable to move said contact element between open and closed positions, snap operating mechanism interposed between said operating member and said contact element for moving said contact element with a snap action, said snap operating mechanism including a cam associated with said operating member, and an actuated part yieldingly held in engagement with said cam and releasably connected to said contact element, and an overload mechanism responsive to release said actuated part from said contact element, said operating member being operable

to reset said overload mechanism and to reconnect said actuated part to said contact element.

4. A switch device having a movable contact element biased towards open position, a manual operating member having a cam associated therewith, an actuated part releasably connected to said contact element and yieldingly held in engagement with said cam, said operating part being movable with a snap action by said cam upon reciprocating movements of said operating member, an overload mechanism responsive to release said actuated part from said contact element, said operating member when moved into a position to effect opening of said switch providing for resetting of said overload mechanism and for reconnection of said actuated part to said contact element.

5. In an electric switch, in combination, a reciprocable contact element biased towards open position, operating means therefore including a pivoted operating part and a releasable operating connection between said operating part and said contact element adapted to be tripped to free said contact element from restraint by said operating part, and an electro-thermally controlled device of the solder type having a spring biased part releasable automatically under given electrical conditions to trip said operating connection, and means associated with said operating means for resetting said spring biased part upon release thereof and for also effecting resetting of said operating connection.

6. In an electric switch, in combination, a reciprocable contact element biased towards open position, operating means therefor including a manual operating part and a latch connection between said operating part and said contact element adapted to be tripped to free said contact element from restraint by said operating part, and an electro-thermally controlled device of the solder type having a spring biased part releasable automatically under given electrical conditions to trip said latch, and means associated with said operating means for resetting said spring biased part upon release thereof.

7. In an electric switch, in combination, a reciprocable contact element biased towards open position, operating means therefore including a manual operating part and an operating connection between said operating part and said contact element including a latch adapted to be tripped to free said contact element from restraint by said operating part, and an electro-thermally controlled device of the solder type having a spring biased part releasable automatically under given electrical conditions to trip said latch, said operating part when moved to a position to effect opening of said contact element being adapted to reset said latch and said spring biased part.

8. In an electric switch, in combination, an insulating base having a pair of stationary contacts mounted upon the front face thereof, a movable contact element mounted upon said base for bridging said stationary contacts, said

contact element having spring means associated therewith for moving the same away from said stationary contacts, operating means for said movable contact element including a pivoted operating part and a releasable operating connection between said operating part and said contact element adapted to be tripped to free said contact element from restraint by said operating part, an electro-thermally controlled device of the solder type having a spring biased part mounted upon the rear face of said base and releasable automatically under given electrical conditions to trip said operating connection, and means associated with said operating means for resetting said spring biased part upon release thereof and for also effecting resetting of said operating connection.

9. In an electric switch, in combination, an insulating base having a plurality of pairs of stationary contacts mounted upon the front face thereof, a movable insulating yoke mounted upon said base and having a plurality of bridging contacts associated therewith for engaging each of said pairs of stationary contacts, spring means associated with said yoke for biasing the same and the bridging contacts carried thereby away from said stationary contacts, operating means for said yoke including a manual operating part and a releasable operating connection between said operating part and said yoke adapted to be tripped to free said yoke from restraint by said operating part, a plurality of electrothermally controlled devices of the solder type mounted upon said base, each of said devices including a heater connected to certain of said stationary contacts and a spring biased tripping part releasable automatically under given electrical conditions in said heater to trip said operating connection, and means associated with said operating means for resetting any or all of said spring biased tripping parts upon release thereof and for also effecting resetting of said operating connection.

10. In an electric switch, in combination, a plurality of pairs of insulated stationary contacts, a reciprocable insulating yoke having a plurality of bridging contacts yieldingly mounted thereon for engaging each of said pairs of stationary contacts, said yoke being biased to disengage said bridging contacts from said stationary contacts, operating means for said yoke including a manual operating part and a latch connection between said operating part and said yoke adapted to be tripped to free said yoke from restraint by said operating part, a plurality of electrothermally controlled devices of the solder type, each of said devices including a heater connected to certain of said stationary contacts and a spring biased tripping part releasable automatically under given electrical conditions in said heater to trip said latch, said operating part when moved to a position to disengage said bridging contact from said stationary contacts being adapted to effect resetting of said latch and any or all of said tripping parts.

CLARENCE W. KUHN.
